No. 841,420

PATENTED JAN. 15, 1907.

J. P. NIKONOW,
BOTTLE CLOSURE.
APPLICATION FILED JUNE 5, 1906.

UNITED STATES PATENT OFFICE.

JOHN P. NIKONOW, OF PITTSBURG, PENNSYLVANIA.

BOTTLE-CLOSURE.

No. 841,426.

Specification of Letters Patent.

Patented Jan. 15, 1907.

Application filed June 5, 1906. Serial No. 320,308.

To all whom it may concern:

Be it known that I, JOHN P. NIKONOW, a subject of the Czar of Russia, residing at Pittsburgh, in the county of Allegheny and 5 State of Pennsylvania, have invented certain new and useful Improvements in Bottle-Closures, of which the following is a specification.

This invention provides a closure for bottles, jars, boxes, and like packages which is 10 adapted to be held against casual displacement and which may be made secure when properly closed.

The invention consists, primarily, of a band, ring, or collar adapted to encircle the 15 neck portion of the bottle, jar, or like receptacle or to be secured to the sides of the box or package near the opening which is protected by the closure or cover and a cover or closure having a rim portion to embrace the band, ring, or collar and adapted both to slip and partly turn thereon, said cover having a bayonet-slot in its rim to receive one member of a bow or staple fastening secured to the said band, ring, or collar.

25 For a full description of the invention and the merits thereof and also to acquire a knowledge of the details of construction of the means for effecting the result reference is to be had to the following description and 30 accompanying drawings.

While the invention may be adapted to different forms and conditions by changes in the structure and minor details without departing from the spirit or essential features 35 thereof, still the preferred embodiment is shown in the accompanying drawings, in which—

Figure 1 is a perspective view of the upper portion of a bottle or jar provided with a closure embodying the invention. Fig. 2 is a 40 vertical central section of the parts illustrated in Fig. 1. Fig. 3 is a horizontal section on the line $x-x$ of Fig. 2. Fig. 4 is a detail perspective view of opposite ends of a 45 strip which when bent forms the band, ring, or collar. Fig. 5 is a view similar to Fig. 2 of a modification, showing the cover thrown open.

Corresponding and like parts are referred to in the following description and indicated 50 in all the views of the drawings by the same reference characters.

The numeral 1 indicates a jar or bottle which is typical of the class of devices for which the invention is designed.

The numeral 2 designates a band, ring, or 55 collar which encircles and is fitted to the neck of the bottle or other receptacle or package and which part 2 may be of any construction and secured to the receptacle in any way. The part 2 is usually formed of a metal strip, 60 which is fitted about the neck or sides of the article and has its end portions joined either by means of a lock-seam, as 3, or by means of a tongue 4 and slot 5, the latter being formed in an end portion of the strip from 65 which the part 2 is formed and the tongue 4 being partly cut and pressed outward from the opposite end of said strip, the tongue 4 being adapted to be passed through the slot 5 and bent, as will be readily understood. 70

In the case of a bottle, jar, or the like the band or collar 2 is prevented from outward displacement by means of an outer rib or lip formed at the upper end of the neck. The cover 6 is of the form of a cap and comprises 75 a rim which embraces the part 2. The cover may be formed of any material and when constructed of paper pressed into shape is reinforced at its edge by means of a metal binder 7, which embraces said edge, to which 80 it is secured by having the edge of its sides inturned or in any desired way. A bayonet-slot 8 is formed in the rim of the cover and receives a member of the fastening 9, which is of bow or staple form and attached to the 85 band, ring, or collar 2 in any substantial manner.

When the cover is in position so as to close the mouth of the bottle, jar, or the like or the open side of the box or package, its rim 90 overlaps the part 2 and the member of the fastening 9 occupies a position at the end of the horizontal member of the bayonet-slot opposite to the vertical member of said slot, as shown most clearly in Fig. 1. When the 95 parts occupy this position, the cover may not be accidentally displaced, and to open the bottle or package it is necessary to partly turn the cover to bring the vertical member of the bayonet-slot in register with the fastening 9, after which said cover is moved outward to bring the member of the fastening passed through the slot in the lower end of the vertical member of said slot, after which the cover may be thrown open as upon 100 a hinged joint.

It is proposed to construct the closure in different sizes, so that the proper size may be

selected and fitted to the bottle or other form of receptacle or package.

It is also contemplated to fit the closure to bottles and packages of like nature before placing the same upon the market.

It is noted that while the cover may be thrown open it cannot become misplaced, by reason of its permanent connection with the bottle or package.

10 In order to obtain a tight joint between the cover and bottle or like receptacle 1, a packing 10 of rubber or other suitable material is fitted in the upper portion of the cover, so as to be confined between it and the end of 15 the receptacle to which the closure is applied.

In order that the cover may be secured at different points in its circumference, it is proposed to provide one or more bayonet-slots 20 11 in addition to the bayonet-slot 8, the vertical member of said bayonet-slot opening through the lower edge of the rim of the cover to admit of a pin or stud 12, affixed to the band or collar 2, entering said bayonet when 25 pressing the cover upon the bottle or receptacle to be closed. A notch 13 is arranged at the inner end of the horizontal member of the bayonet-slot 8 to receive the upper member of the fastening 9, so as to prevent casual 30 turning of the cover after the parts have been properly positioned. An independent notch 14 is formed at the inner end of the horizontal member of the bayonet-slot 11 to receive the pin or stud 12 for a like purpose.

Having thus described the invention, what 35 is claimed as new is—

1. A closure for bottles, packages and the like comprising a band, a cover having a rim to encircle said band, and a permanent connection between the band and cover comprising a bayonet-slot and a fastening of bow form having a member passed through said bayonet-slot.

2. A closure for bottles, packages and the like comprising a band, a cover having a rim 45 to embrace said band and provided with a bayonet-slot, and a fastening of bow form secured to the band and having a member passed through said bayonet-slot, the cover adapted to have a threefold movement, a 50 partial turning, a slip-joint and a swinging movement.

3. A closure for bottles, packages and the like comprising a strip adapted to be bent upon itself to form a band for encircling the 55 neck or like portion of a bottle or kindred package, a cover having a rim to encircle said band and provided with a bayonet-slot, and a fastening of bow form secured to said band and having a member passed through the 60 bayonet-slot.

In testimony whereof I affix my signature in presence of two witnesses.

JOHN P. NIKONOW. [L. S.]

Witnesses:

BIRNEY HINES,
VERYL B. BROUGHTON.
